EMANUEL HENRIKSON, OF WETHERSFIELD, AND ARTHUR L. FREDERICKSON, OF HARTFORD, CONNECTICUT, ASSIGNEES TO PRATT & WHITNEY COMPANY, OF HARTFORD, CONNECTICUT, A CORPORATION OF NEW JERSEY.

LOCKING MECHANISM.

1,233,666.

Specification of Letters Patent. Patented July 17, 1917.

Application filed October 12, 1916. Serial No. 125,308.

To all whom it may concern:

Be it known that we, EMANUEL HENRIKSON and ARTHUR L. FREDERICKSON, citizens of the United States, residing at Wethersfield and Hartford, respectively, in the county of Hartford and State of Connecticut, have invented certain new and useful Improvements in Locking Mechanism, of which the following is a specification.

10 This invention relates to locking mechanism. While locking mechanism involving our invention is susceptible of general use, it is of particular utility when incorporated in or forming part of a turret lathe, being intended in this field to lock the turret in its indexed position. The bolt is advanced by a spring and one of the primary purposes of the invention is the provision of means whereby the effect of the spring is virtually only utilized when the bolt is in active position and also when it is being moved to such relation, the spring at such times being capable of applying a powerful yet slow thrust to the bolt. In the case of a turret, there will be a plurality of said bolts, generally two.

15 20 25

In the drawings accompanying and forming part of the present specification we have shown in detail one convenient form of embodiment of the invention which will be set forth fully in the following description. We do not restrict ourselves to this exact disclosure; we may depart therefrom in several respects within the scope of the invention defined by the claims following said description.

Referring to said drawings:

Figure 1 is a vertical section of a turret and part of the slide with locking mechanism for the turret, involving the invention.

Fig. 2 is a transverse section on the line 2-2 of Fig. 1, looking in the direction of the arrows and showing the locking ring in full lines, a part of the slide being in section.

Like characters refer to like parts in both views.

The use of this locking mechanism is not restricted to any particular field, but it is of especial advantage when employed in conjunction with a turret of which that denoted by 5 is an example. This turret as

shown turns on the hollow stud or pivot 6 extending from the slide 7, the axis of the turret in the present case being horizontal, although this is a small point as may be inferred. Through the stud or pivot the hollow shafts 8, 9 and 10 extend. These three shafts are concentric and are supported at their rear end portions by the slide 7. The shaft 8 and the adjuncts immediately supported thereby constitute a part of the indexing mechanism and therefore need not be described. The inner shaft 10 constitutes a part of the slide adjusting mechanism, and it therefore, with its accessories requires no description. The intermediate shaft 9 is common to both the indexing and the locking mechanism. At its forward end it may have fastened thereto as by keying the hub of the hand lever 11, acting as a convenient means for turning said shaft 9. The latter at its rear end is shown provided with a collar or band 12 having the upstanding arm 13 by which other suitable instrumentalities not a part of the present invention, sets the indexing mechanism into action. With this collar or band, however, is associated means whereby the locking mechanism hereinafter more particularly described is operated. The rear portion of the turret 5 has an inwardly extending flange 14 providing a rabbet to receive the ring 15, acting as a suitable keeper for one or more bolts, this ring being united to the turret in some convenient way, as by the pins 16 of which there may be any suitable number. The ring has on its back the segments 17, the outer surfaces 90 of which are flush with the circumference of the ring. These segments are separated as at 18 to produce bolt-receiving spaces. The several segments 17 might be considered to be a slotted or interrupted flange, the slots 95 being the spaces 18 and two diametrically opposite slots being adapted to simultaneously receive the tip portions of bolts as 19 which are readily movable toward and from the axis of motion of the turret. As shown there are two of these bolts, although this may not always be necessary. It is generally the custom, however, to provide this number and to have them diametrically opposite as shown. The slide 7 may be equipped with strips as 20 fastened thereto.

as by screws 21, the strips being arranged in pairs and each pair constituting a convenient guide for an intermediate bolt.

In the present case both bolts are advanced by spring means, and although two springs are shown for this purpose, this is not altogether a matter of moment. The spring means of whatever type and number the same may be, acts to hold the bolts advanced and also acts to advance the bolts irrespective of other means acting upon them at a predetermined point in their forward movement. At other times or while the bolts occupy a backward position, the thrust of the spring or springs is not applied thereto.

The results in question may be obtained in a great variety of ways, although means quite suitable for this purpose is illustrated and will now be set forth. Surrounding the outermost hollow or tubular shaft 8 where said shaft extends into the slide 7, is what we consider a bolt actuator 22. This bolt actuator in the organization shown functions as a cam. As illustrated it consists of practically duplicate sections 23 and 24. We speak of these sections as "practically" duplicate; they are, but there is a slight difference between them, as we will hereinafter point out. When the sections 23 and 24 are assembled to produce the actuator or cam, the latter is spaced or separated from the shaft 8, so that said actuator can freely turn without interference from said shaft. The sections 23 and 24 are connected for relative movement, and any suitable means may be provided for this purpose, the screws 25 being shown. The said screws extend through plain bores in the section 24, 40 through sockets as 26 in the section 23, and are threaded into the threaded holes 27 of said sections 23 which open into the respective sockets 26 centrally of the bottoms thereof. The threaded holes 27 receive the screw plugs 28 which back up the tips of the assembling screws 25 and act as adjustable stops to hold said assembling or connecting screws 25 in predetermined adjusted position. The straight flat edges of the sections 23 and 24 it will be noted are separated, the space between them being denoted by 29. It will also be observed that the heads 30 of the connecting screws 25 are also likewise separated from the adjacent section 24. In the sockets 26 are coiled springs 31 fitting against the bottoms of said sockets and also against the inner face of the section 24, the springs surrounding the shanks of the screws 25 and tending constantly to spread or separate said sections 23 and 24. The reason for this will be hereinafter set forth. The bolts 19 are furnished with projections or studs as 32 which may as shown consist of anti-friction rollers extending into the slots 33 of the respective

sections of the actuator 22. Each slot 33 has two portions as 34 and 35, the portions 34 being on arcs struck from the axis of motion of the actuator 22, the portions 33, however, being cammed or bent inwardly. The portions of the respective slots merge into each other gently or without any break, so as to insure proper cam action.

As will be understood the actuator 22 serves as a convenient means for reciprocating the bolts 19 together. When the actuator is turned in one direction or as indicated by the arrow in Fig. 2, the bolts will be retracted or drawn back, whereas on opposite motion of said actuator the advance or forward movements of the bolts will be caused. The hand lever or arm 11 serves as a proper prime agent for effecting through suitable intermediate parts the requisite motion of the actuator. This arm, it will be recalled, is carried by the intermediate shaft 9, having fastened to its rear the collar 12. We have shown in dotted lines in Fig. 2 the arm 11. From the band or collar 12 depends the bent arm or extension 36 which projects into the notch 37 on the section 23 of the actuator 22. The arm 11 is shown as occupying its normal position in said Fig. 2. When it is swung up the bent extension 36 will be moved toward the observer in Fig. 1, thus causing the actuator 22 to follow the arrow applied thereto in Fig. 2. This causes the two rollers 32 to travel along the ineffective or concentric portions 34 of the two slots 33 and enter the active or cam portions 35 of said slots. As soon as the rollers enter the cam or effective portions of the slots, the bolts are retracted. On opposite motion the reverse action occurs.

It will be noted that the springs 31 tend constantly to separate the sections 23 and 24. When, therefore, the studs or rollers 32 have passed into the effective portions 35 of the two slots the springs will have so separated the sections 23 and 24 that the section 24 will abut against the screw heads 30, thus preventing further movement apart of the two sections beyond which point or as the actuator 22 continues to turn, the rollers 32 will enter the effective portions 33, the actuator at this time being virtually a rigid plate so as to non-yieldingly draw back the two bolts which have been drawn out of their notches 18. On the backward movement of the actuator or in a direction opposite that shown by the arrow in said Fig. 2, the cam portions 33 advance the bolts and just about the time the anti-friction rollers or studs 32 enter the ineffective portions of the slots 34, the section 24 will have passed free of the heads 30, so that the springs 31 become effective for again separating said sections 23 and 24 and through the latter applying their effect to the bolts to slowly yet

powerfully advance the same to move the tips of the bolts into the notches 18 to lock the turret in its indexed position.

It will be clear that the effect of the springs 31 is taken from the two bolts 19 just after the latter have commenced their retractive movement, which in the present case occurs just about the moment the studs or anti-friction rollers 32 enter the cam portions 35 of the slots 33. At this time the actuator 22 is being advanced. At approximately the point this occurs the separation of the sections 23 and 24 is arrested by the section 24 striking the heads 30, so that on the final and in fact greater part of the retractive movement of the bolts, there is no spring pressure applied thereto. As the actuator 22 moves in the direction opposite the arrow, the bolts are advanced as the studs travel the effective portions 35 of the slots and just as they enter the ineffective portions 34 thereof, the section 24 will pass free of the heads 30, so that the effect of the springs is then received by the two sections 23 and 24 and applied in turn to the bolts on the final part of the advance movement thereof, so that the bolts will be set with a final, powerful yet slow pressure.

It will be remembered that the bolts are guided by the strips or guide members 20, the opposite faces of which are parallel for this purpose. The outer faces 40 of these guide members are on a taper which is inward; that is to say the outer face of the respective guide members converge inwardly and bear against walls of slots as 41 in the slide 7. The screws 21 to which I have referred are tapped through hollow screws 42 which have a threaded connection with the slide 7. By running these screws 42 inward the guide members 20 can be correspondingly operated and owing to the tapered surfaces 40 bearing against the walls of the slots 41, said guide members will be moved toward each other to take up wear therein.

What we claim is:

1. The combination of a locking bolt, spring means to advance the bolt, means for retracting and advancing the bolt, for removing the pressure of the spring means from the bolt when the same reaches a predetermined point in its retractive movement and for reapplying the pressure of said spring means to the bolt when the latter reaches a predetermined point in its advancing movement.

2. The combination of a rotary turret and its support, a locking bolt for the turret, carried by one of the parts, spring means to advance the bolt, means for retracting and advancing the bolt, for removing the pressure of the spring means from the bolt when the same reaches a predetermined point in its retractive movement, and for reapply-

ing the pressure of the spring means to the bolt when the latter reaches a predetermined point in its advancing movement.

3. The combination of a locking bolt, a spring to advance the bolt, and means for retracting the bolt and for removing the pressure of the spring from the bolt, when the same reaches a predetermined point in its retractive movement.

4. The combination of a locking bolt, an actuator for the locking bolt, a spring acting against the actuator and applying through said actuator its effect to said bolt, and means for operating the actuator to effect the movement of the bolt, the actuator having means to receive the pressure of the spring and for taking the pressure from said bolt when the latter reaches a predetermined point.

5. The combination of a locking bolt, a cam for operating said locking bolt, a spring to apply its effect to the cam and through the cam to the bolt to hold the latter seated, and means for actuating the cam to effect the movement of the bolt, the cam being provided with means to receive the pressure of the spring when the bolt has been moved a certain distance.

6. The combination of a locking bolt having a stud, a rocking cam having a slot to receive the stud, the slot having effective and ineffective portions, means for rocking the cam to move the bolt forward and backward, a spring to apply its effect to the cam and the latter to the bolt when the bolt is in its operative position, and the cam having means to receive the pressure of the bolt about the time the stud enters the effective portion of said slot on the retractive movement of the bolt.

7. The combination of a locking bolt, a rock shaft, a cam for retracting the bolt, connections between the rock shaft and the cam for operating the latter, a spring to apply its effect to the cam and the latter to the bolt, when the bolt is in operative position, the cam having means to receive the pressure of the spring when the cam has reached a certain point in its backward movement.

8. The combination of diametrically opposite locking bolts having studs, a divided cam having slots to receive the respective studs, each slot having effective and ineffective portions, the studs fitting the effective portions when the bolts are in locking position and the cam being divided, spring means tending constantly to separate the sections of the cam, means for limiting the amount of separation of said sections, and means for rocking the cam.

9. The combination of a plurality of locking bolts, a sectional cam, one section being socketed and the other having bores opening into the sockets, both sections having cam slots comprising effective and ineffective

portions, the bolts having studs to enter the ineffective portions when the bolts are in operative positions, screws extending through the bores and tapped into the socketed section of the cam, the screws having heads to limit the amount of separation of the sections of the cam, and springs in said sockets, tending constantly to separate the sections.

10. The combination of a plurality of locking bolts, a sectional cam, one section being socketed and the other having bores opening into the sockets, both sections having cam slots comprising effective and ineffective portions, the bolts having studs to enter the ineffective portions when the bolts are in operative positions, screws extending

though the bores and tapped into the socketed section of the cam, the screws having heads to limit the amount of separation of the sections of the cam, and springs in said 20 sockets, tending constantly to separate the sections, and other screws backing up the first mentioned screws and carried by the socketed section.

In testimony whereof we affix our signatures in the presence of two witnesses.

EMANUEL HENRIKSON.
ARTHUR L. FREDERICKSON.
